(57) **CLAIM**

The ornamental design for lever door handle lock, as shown and described.

DESCRIPTION

FIG. 1 is a front perspective view of the lever door handle lock;

FIG. 2 is a front view of the lever door handle lock of FIG. 1; FIG. 3 is a rear view of the lever door handle lock of FIG. 1; FIG. 4 is a right side view of the lever door handle lock of FIG. 1;

FIG. 5 is a left side view of the lever door handle lock of FIG. 1;

FIG. 6 is a top view of the lever door handle lock of FIG. 1; and,

FIG. 7 is a bottom view of the lever door handle lock of FIG. 1.

The broken lines shown are included for illustrative purposes only and form no part of the claimed design. The dash-dot-dash broken line shown in the drawings defines a boundary of the claimed design.
